ROLL GRINDING MACHINE

Norman J. Ritzert, Dayton, Ohio, assignor to The Dayton Rubber Manufacturing Company, Dayton, Ohio, a corporation of Ohio

Application May 10, 1937, Serial No. 141,684

7 Claims. (Cl. 51—95)

This invention relates to abrading machinery, and in particular, to a machine for accurately surfacing cylindrical rolls, such as rubber-covered rolls for printing machines.

One object of this invention is to provide a roll grinding machine, wherein the roll is urged against the rotatable grinding member by a second roll, thereby preventing the bulging and uneven grinding of the surface of the roll.

Another object is to provide a machine for grinding rolls composed of yielding material, the machine being arranged in such a manner that the roll is engaged by a contact roller on one side thereof, and engages the grinding element on the opposite side so that bulging of the yielding material at diametrically opposite points is effectively prevented.

Another object is to provide a roll grinding machine of this character, wherein means is afforded for accurately controlling the parallelism of the roll-supporting shaft with the shaft of the grinding element.

Another object is to provide a roll grinding machine, wherein the roll is mounted upon a carriage which is reciprocable longitudinally and movable transversely of the grinding element shaft.

Another object is to provide a roll grinding machine, wherein the roll-supporting means and a contacting member for aligning the material of the roll are arranged upon a carriage which is adapted to be movable both longitudinally and laterally of the grinding element shaft.

Another object is to provide a roll grinding machine, wherein the roll of yieldable material to be ground is engaged by a contact roll mounted upon swinging arms having means associated therewith not only for accurately swinging the arms but also for rotating the contact roll.

Another object is to provide a roll grinding machine, wherein the grinding element consists of a cylindrical drum having a spirally wound strip of abrasive material mounted thereon.

Another object is to provide a roll grinding machine of the type set forth immediately above, wherein improved means is provided for securing the strip of abrasive material to the supporting drum at the opposite ends thereof.

In the drawings:

Figure 1 is a front elevation of the roll grinding machine of this invention.

Figure 2 is a right-hand end elevation of the machine shown in Figure 1.

Figure 3 is a vertical section taken along the line 3—3 of Figure 1.

Figure 4 is a section along the line 4—4 in Figure 1, showing the right-hand end of the grinding drum.

Figure 5 is a top plan view of the right-hand end of the grinding drum shown in Figure 1.

Figure 6 is a section, similar to Figure 4, taken along the line 6—6 in Figure 1, but showing the left-hand end of the grinding drum.

Figure 7 is a top plan view of the left-hand end of the grinding drum shown in Figure 6.

Figure 8 is a section along the line 8—8 in Figure 1, showing the means for supporting the right-hand end of the roll to be ground.

Figure 9 is a left-hand side elevation of the structure shown in Figure 8.

Figure 10 is a cross section taken along the line 10—10 in Figure 1, showing the means for regulating the alignment of the roll to be ground.

Figure 11 is a left-hand side elevation of the structure shown in Figure 10.

Hitherto, grinding machines for abrading the surfaces of work rolls, such as printing or coating rolls, have provided mechanism which urged one side of the work roll into engagement with the grinding drum. Ordinarily, such work rolls are of yielding or resilient material, such as natural or synthetic rubber. The pressure by which the roll was urged into engagement with the grinding drum, under such circumstances, caused the work roll to bulge because of its resilient construction, this bulging reaching its maximum diametrical the line of contact with the grinding drum. The result of such prior devices was to cause a concavity or hollowed zone around the central portion of the roll. The machine of the present invention provides means for engaging the work roll on a line diametrically opposite the line of engagement of the work roll with the grinding drum, and therefore, to a large extent reduces this bulging effect with its resulting hollow grinding or concavity of the work roll.

In general, the roll grinding machine of this invention consists of a cylindrical drum having a spirally wound strip of abrasive material, such as emery cloth or sandpaper, firmly secured thereto. The roll to be ground ordinarily consists of yielding material, such as rubber, such rolls being used in printing, coating and paper-making machinery. It is important that such rolls have a true cylindrical surface and not a conical or concaved surface. Any such deviations from a true cylindrical surface interfere with the proper action of the roll and detract

from the quality of the work turned out by the machine in which it is used.

The present machine embodies means for accurately adjusting the roll in the machine so as to prevent its being ground conically, and also has other means engaging the roll for preventing uneven grinding of the surface. To this end the roll to be ground is supported upon devices enabling the adjustment of the roll shaft until it is in true parallel relationship with the shaft of the grinding drum, thereby preventing conical grinding. To prevent uneven grinding, the roll to be ground is engaged on the opposite side from the drum by a pressure roll having a true cylindrical surface and bearing against the yielding roll in such a manner as to reduce the bulging effect of the yielding material which would otherwise occur.

Referring to the drawings in detail, Figures 1 and 2 show one embodiment of the grinding machine of this invention as consisting of a frame, generally designated 10, having supporting members 11 for supporting a bed 12 (Figure 2) with parallel ways or ridges 13 and 14 thereon. Between each adjacent pair of ridges 13 and 14 is a level portion 15 which serves to receive the grinding drum supporting members 16 (Figure 2). Mounted upon the upper portion of the supporting members 16 are bearing blocks 17 arranged to rotatably support the shaft 18 of the grinding drum, generally designated 19. Superimposed upon the shaft 18 and bearing blocks 17 are the bearing members 20 forming the upper half of each bearing.

35

Grinding drum construction

The grinding drum 19 consists of a hollow cylinder having discs 21 and 22 at its right and left-hand ends (Figures 5 and 7). The discs 21 and 22 are provided with hubs 23 and 24 with set screws 25 and 26 for securing these hubs to the shaft 18. Ring-shaped members 27 and 28 are welded, as at 29, to the discs 21 and 22, and serve to support the cylindrical portion of the grinding drum 19 (Figures 5 and 7). Angularly disposed slots 30 and 31 extending inwardly from the ends of the grinding drum 19 serve to receive the opposite ends of the abrasive material strip 32. The latter consists of a long strip of abrasive material, such as emery cloth wound in a spiral path around the drum, as shown in Figure 1.

The right-hand end of the abrasive strip 32 passes through the slot 30 (Figure 4) around the rounded edge 33 over a semi-cylindrical member 34 secured, as by the set screws 35, to the under side of the ring member 27. Likewise secured to the ring member 27, as by the cap screws 36, is a clamping member 37 having a concave mating cylindrical surface 38 adapted to engage the opposite side of the abrasive strip 32 from that engaged by the convex cylindrical surface of the member 34. At its opposite end the clamping member 37 is provided with a convex cylindrical projection 39 which clamps the extreme end of the abrasive strip 32 against the inner wall of the ring-shaped member 27. By tightening the cap screws 36 the clamping member 37 is caused to anchor the end of the abrasive strip 32 securely to the ring member 27.

70 The abrasive strip 32 then follows a spiral path around the grinding drum 19 to the opposite end thereof, where it passes through the slot 31, the latter being arranged obliquely through the end of the grinding drum 19 (Figures 6 and 7). After 75 passing through the slot 31 the end of the abra-

sive strip 32 is securely clamped within the V-shaped portion 40 of the swinging arm 41, as by the correspondingly shaped wedge member 42, clamped in position by the cap screw 43. The inner end of the swinging arm 41 is attached, by 5 a pivot screw 44, to the boss 45 of the hub 24. The arm 41 is provided with a lug 46 having a hole 47 for receiving one end of a tension spring 48, the opposite end of which is anchored, as at 49, to the lug 50 secured, as by welding, to 10 the inner side of the ring-shaped member 28. Consequently, it will be seen that when the abrasive strip 32 is clamped at the right-hand end of the grinding drum 19, in the manner shown in Figure 4, and is wound spirally around 15 the drum to the left-hand end thereof, the arm 41 to which the free end of the abrasive strip 32 is anchored, maintains the strip 32 in a taut condition by means of the tension spring 48.

Carriage construction

20

Mounted for reciprocation along the ways 13 (Figure 2) is a carriage 51 having grooves 52 corresponding to the ridges or ways 13, held in engagement therewith by the retaining plates 53. Secured to the under side of the carriage 51 is a stud 54 (Figure 1) upon which is mounted an anti-friction roller 55, provided with bearing balls 56. The outer race of this roller 55 engages the cam groove 57 of a cam 58 mounted upon a 30 shaft 59, supported in journals 60 and 61 upon the frame of the machine. The shaft 59 is provided with a sprocket 62 having a hub 63 drivingly and slidably secured thereto, as at the splined portions 64. The sprocket 62 is engaged by a sprocket chain 65 leading to a driving motor (not shown) by which the cam shaft 59 may be rotated. The rotation of the cam shaft 59 causes the cam groove 57 of the cam 58 to reciprocate the carriage 51 by its engagement with the roller 55 mounted thereon.

35

Secured to the carriage 51, as by the screws 66, is a support 67 (Figures 1 and 2) for the screw shaft 68, the threaded portion of which engages a nut 69 secured by the screws 70 to a cross slide 71. Mounted on the screw shaft 68 is a hand wheel 72 by which the screw shaft 68 may be rotated for moving the cross slide 71 transversely across the carriage 51. For this purpose the carriage 51 and cross slide 71 are provided with cooperating dove-tailed ridges 73 and 74, 50 respectively.

45

Integral with the cross slide 71 and rising therefrom are spaced bearing bosses 75 (Figure 1) having bores 76, which rotatably support a shaft 77 having arms 78 and 79 mounted on its 65 opposite ends. Mounted on the extreme right-hand end of the shaft 77 is a worm gear 80 having its threads meshing with the worm 81 mounted upon the worm shaft 82. The latter is supported at its opposite ends by the bearing bosses 83 and 84, respectively, and provided with anti-friction thrust bearings 85 and 86 for resisting the thrust of the worm 81. A spacing sleeve 87 is arranged between the boss 84 and 60 thrust bearing 85 (Figure 3).

55

Mounted upon the shaft 59 and slidably and drivingly connected thereto by the splined portions 64, is a sprocket 88 (Figure 1) meshing with a sprocket chain 89 which passes around 70 and drives a sprocket 90, the hub of which rotates loosely upon the shaft 77 and carries a gear 91. A yieldingly urged idler sprocket (not shown) is mounted on the cross slide 71 in a conventional manner to adapt the sprocket chain 89 to 75

the changing distance between the centers of its sprockets 88 and 90 as the cross slide 71 is moved transversely. The gear 91 meshes with a pinion 92 mounted upon a stud 93, which in turn, 5 is mounted upon the swinging arm 79. The pinion 92 meshes with a pinion 94 similarly mounted upon a stud 95, and this pinion 94 in turn meshes with a pinion 96 mounted upon the pressure roll shaft 97, rotatably supported in the bores 98 and 99 of the arms 78 and 79, respectively.

Accordingly, when the shaft 59 is rotated by the sprocket chain 65 from the driving motor, the pressure roll shaft 97 is rotated through the train of gears 91, 92, 94 and 96, and rotates a pressure roll 100 carried by the pressure roll shaft 97. The pressure roll 100 may consist of metal, hard rubber, synthetic resin or other suitable material, hard rubber having been found suitable in one installation of the machine. The pressure roll 100 is provided with an accurate cylindrical surface 101 which serves to engage a work roll 102, such as a printing roll or other roll which is to be ground in the machine. The pressure roll 100 may be swung to and fro toward 20 and away from the work roll 102 by turning the hand wheel 103, mounted upon the outer end of the worm shaft 82. When this hand wheel 103 is rotated the rotation of the worm shaft 82 rotates the worm 81 and with it the worm gear 80 rigidly mounted upon the shaft 77, thereby swinging the arms 78 and 79 also rigidly mounted thereon.

Work roll supporting construction

Integral with the cross slide 71 and rising from the opposite ends thereof are pillars 104, the top portions of which are provided with bores 105 for supporting the opposite ends of a shaft 106, rigidly mounted therein. The shaft 106 is provided with a groove 107 having approximately V-shaped tapering walls (Figure 3). Arranged upon the right-hand end of this shaft 106 is a downwardly extending arm 108 (Figures 1 and 8) for supporting the right-hand end of the 25 work roll 102. The arm 108 is provided with a hub 109 (Figure 8) with a threaded portion 110 adapted to receive a cap screw 111, which engages the rear portion 112 of a wedge-shaped member 113 to force the latter into the groove 107 of the shaft 106, thereby anchoring the arm 108 securely in any desired position along the shaft 106. The vertical portion 114 of the arm 108 is provided with a cut-away portion 115 having a plurality of holes 116 adapted to receive dowel pins 117 for aligning a bar 118 having corresponding holes 119 for receiving the dowel pins 117. This construction is provided for enabling the bar 118 to be raised or lowered and anchored securely in any one of a plurality 30 of positions, as determined by the dowel pins 117 in the holes 116. A cap screw 120 passes through a threaded bore 121 in the arm portion 114 and engages the opposite edge of the bar 118 from the dowel pins 117, thereby firmly securing the bar 118 in position. The lower portion of the bar 118 is provided with a rounded notch 122 for receiving the shaft 123 of the work roll 102, the latter being the printing roll or coating roll which is to be evenly ground in the machine.

70 In order to hold the work roll shaft 123 securely within the notch 122, a clamping arm 125 is provided having its forward end engaging the work roll shaft 123. The opposite end of the arm 125 is provided with a smooth bore 126 surrounding the threaded end 127 of a downwardly

extending rod 128, the upper portion of which is adapted to move vertically within a vertical bore 129 and to be clamped in position by a cap screw 130 passing through a threaded bore 131 in a boss 132 on the arm portion 114 (Figure 8). 5 A knurled nut 133 serves to hold the clamping arm 125 firmly in engagement with the work roll shaft 123 within the notch 122, and at the same time, to permit the arm 125 to be swung to one side in order to enable the rapid removal and 10 insertion of additional work rolls 102.

Likewise mounted upon the shaft 106 is an additional work roll support 134 having a similar function to the work roll support 108, but with an additional adjustment for insuring the parallelism of the work roll shaft 123 with the grinding drum shaft 18. This adjustment prevents the grinding of a conical surface upon the roll 102. For this purpose the support 134 consists of two relatively movable portions, namely, a pulley-like hub 135 mounted upon the shaft 106, and a supporting arm 136 mounted upon the hub 135 so as to be slightly movable around this hub. The hub 135 consists of a sleeve-like portion 137 and an end flange 138 having a cap screw 139 20 adapted to engage the back 140 of a wedge 141 and force the latter into the groove 107. By tightening the cap screw 139 the hub 135 may be securely anchored in any desired position longitudinally along the shaft 106.

The sleeve-like portion 137 of the hub 135 is provided with a recess 142 which is accurately machined therein and which is engaged by the eccentric head 143 of a rotatable pin 144 mounted in the bore 145 of the encircling portion 146 35 of the supporting arm 136. The pin 144 likewise passes through a boss 147, to which is secured an index pointer 148, as by the screw 149. Secured, as at 150, to the outer end of the pin 144 is a micrometer drum 151, the graduations 152 of 40 which serve to indicate the position of the eccentric head 143 within the recess 142. A handle 153 is provided in the extreme outer end of the pin 144 for turning the eccentric head 143 thereof. The turning of the eccentric head 143 with- 45 in the walls of the recess 142 causes the encircling portion 146 and the arm 136 to swing around the shaft 106 and relatively to the hub portion 135, thereby moving the left-hand end of the work roll shaft 123 relatively to the right-hand end 50 thereof. The work roll shaft 123 is supported in the arm 136 in a manner similar to the support of the opposite end thereof in the arm 114 of the support 108, hence, the corresponding parts bear similar reference numerals. The left-hand 55 end of the work roll shaft 123 may therefore be raised and lowered and clamped in position in a manner identical with that of the right-hand end, previously described in connection with the description of the support 108.

The encircling portion 146 of the arm 136 is in the form of a split hub having projecting portions 154 and 155 with tangential threaded bores 156 and 157 engaged by the threads of a clamping screw 158, the outer end of which carries an enlarged portion 159 with a transverse hole 160, carrying a handle 161. By turning the handle 161 the projecting portions 154 and 155 may be caused to approach one another, and the encircling portion 146 of the arm 136 may be securely clamped in position after it has been adjusted by rotating the pin 144, in the manner previously described. A face plate 162 (Figure 10) is secured to the right-hand end of the sleeve- 70 75

like portion 137, as by the set screws 163, thereby retaining the parts in position.

Operation

5 The grinding drum shaft 18 is rotated by means of pulleys 183 and belts 164 leading to a suitable driving motor (not shown). The work roll 102 is inserted in its supports 108 and 134, in the manner previously described, and adjusted 10 so as to bring its shaft accurately into parallelism with the shaft 18 by the operations set forth above. The pressure roll 100 is then brought into engagement with the rearward surface of the work roll 102 by turning the hand wheel 103 so 15 that the yielding surface of the work roll 102 is supported longitudinally along its entire extent. The cross slide 71 is then moved forwardly by turning the hand wheel 72 until the work roll 102 approaches the grinding drum 19. 20 Meanwhile, the operation of the sprocket chain 65 has caused the rotation of the pressure roll 100 and likewise the longitudinal feeding movement of the carriage 51 by its engagement with the cam 58. Consequently, the engagement of 25 the pressure roll 100 rotates the work roll 102, and the engagement of the latter with the abrasive strip 32 upon the grinding drum 19 rapidly and evenly removes the material from the work roll 102. The formation of uneven ridges or 30 grooves is prevented by the action of the cam 58 moving the carriage 51 longitudinally along the bed of the machine. The engagement of the even surface of the pressure roll 100 prevents the grinding drum 19 from causing portions of the 35 work roll 100 to bulge rearwardly, and thereby causing concavities in the work roll 102.

It will be understood that I desire to comprehend within my invention such modifications as come within the scope of the claims and the invention.

40 Having thus fully described my invention, what I claim as new and desire to secure by Letters Patent, is:

1. In combination, a bed having ways, a carriage movable along said ways, a rotatable abrading member mounted adjacent said carriage, means for reciprocating said carriage relatively to said abrading member, means for supporting a work roll upon said carriage, means including a pressure roll for urging said work roll into engagement with said abrading member, a swinging mount for holding said pressure roll, and micrometric means for adjustably moving one portion of said swinging mount relatively to another portion thereof to adjust the position of the axis of rotation of said pressure roll relatively to the axis of rotation of said abrading member.

2. In combination, a rotatable abrading member, a pair of spaced uprights, a shaft extending between said uprights and supported thereby, a pair of spaced arms depending from said shaft, means on said arms for supporting a work roll in engagement with said abrading member, said

work roll having a shaft supported by said supporting means, micrometrically adjustable means for swinging one arm relatively to the other arm to move one end of said roll shaft relatively to the other end to adjust the axis of said work roll relatively to the axis of rotation of said rotatable abrading member, and means for rotating said work roll.

3. In combination, a rotatable abrading member, a pair of spaced uprights, a shaft extending between said uprights and supported thereby, a pair of spaced arms depending from said shaft, means on said arms for supporting a work roll in engagement with said abrading member, micrometrically adjustable means for adjustably swinging one arm relatively to the other arm to move one end of said work roll relatively to the other end to adjust the axis of said work roll relatively to the axis of rotation of said abrading member, a pressure roll arranged to engage said work roll on the side opposite its line of engagement with said abrading member, and means for rotating said pressure roll.

4. In combination, a rotatable abrading member, a frame, a carriage movable along said frame axially of said rotatable abrading member, a cross slide mounted on said carriage, means upon said cross slide for supporting a work roll, a plurality of swinging members mounted on said cross slide, means for adjusting one of said swinging members micrometrically relatively to the other swinging member, means on said swinging members for engaging said work roll on the side opposite said abrading member, and a train of gears mounted upon one of said swinging members for rotating said work-engaging means.

5. A device for adjustably holding a roll comprising an elongated member, a plurality of arms supported thereby, a hub-like member arranged between one arm and said elongated member, and micrometrically adjustable means for moving said arm relatively to said hub-like member.

6. A device for adjustably holding a roll comprising an elongated member, a plurality of arms supported thereby, a hub-like member arranged between one arm and said elongated member and having an abutment, a cam mounted on said last-mentioned arm in engagement with said abutment, and means for rotating said cam against said abutment whereby to swing said arm relatively to said hub-like member.

7. A device for adjustably holding a roll comprising an elongated member, a plurality of arms supported thereby, a hub-like member arranged between one arm and said elongated member and having a circular recess, a shaft rotatably mounted on said last-mentioned arm, an eccentric on said shaft disposed in said recess, and means for rotating said shaft to rotate said eccentric in said recess whereby to swing said arm relatively to said hub-like member and to the other arm.

NORMAN J. RITZERT.
